MEANS FOR COMPLETING THE PACKAGING
OF BERRIES OR THE LIKE

Gale Harrison, Ivanhoe, N. C.

Application April 25, 1944, Serial No. 532,570

11 Claims. (Cl. 226—19)

This invention relates to a new and improved means for completing the packaging of berries in the usual type of boxes.

In my application, Serial No. 523,389, filed February 22, 1944, I have shown and described one type of apparatus and process for completing the packaging of berry boxes or containers.

In my Patent No. 2,318,483, issued May 4, 1943, I have disclosed means for what is known in the trade as "topping" the boxes of berries after they are brought in from the field to the packing house. After the topping operation is performed, it is necessary to apply a Cellophane cover over the top of the berries and the box to hold the berries in the box during shipment and distribution. The above-mentioned application discloses a new type of cover and means for applying it to the top of the box. Since inventing the subject matter of said application and working with the structure disclosed therein, I have discovered and developed an apparatus for speeding up the time involved in the application of the cover to the box. I have found, in working with the structure of said application, that when the berry boxes are somewhat warped, as they occasionally are, a little time was lost in getting the boxes inserted on the topping apparatus where the spreader pins are in permanently fixed position. After studying and watching the covering operation, I have discovered how to do it better and faster and with less skill on the part of the operator.

It is therefore the principal object of my invention to provide means for completing the packaging of berries which will overcome the difficulties referred to and attain the advantages pointed out.

While attaining the principal object, I have found, as another object, that unskilled persons can be more quickly trained with my new and improved apparatus which is set forth in the annexed drawings, wherein:

Figure 1 is a plan view of the base portion of my new apparatus, with the box in place on the structure and the spreader fingers moved apart, ready to receive the cover.

Figure 2 is a plan view of the structure of Figure 1, but with the box removed.

Figure 3 is a front view of the structure with the topper turned back and showing the cover in place, ready for the box to be removed from the apparatus (no berries being indicated).

Figure 4 is a view substantially full size, on the line 4—4 of Figure 2 certain parts being shown in elevation.

5 container. Each of the standards or spreader members 7 has its inside surface tapered outwardly for the greater part of its length from a point 8 to its top or apex 9, which tapered surface generally conforms to the slant of the berry box. Pivoted to each of the spreader members 7, by a pin 10, is a lever 11 having a vertically extending arm 12 and a horizontally extending arm 13. The arm 12 tapers inwardly as indicated by the line 14, and then upwardly at 15, terminating in a final taper 16, which portion extends a short distance 17, above the apex 9 of the fixed spreader member 7. As shown in Figures 2 and 4, the upper portions terminating in the ends 9 and 16 are normally in contact so as to form, in effect, a unitary wedge surface which is adapted to be inserted between the body part of the box and the band top as will be later referred to.

10 20 The horizontal arm 13 extends inwardly toward the center and has a reduced end 18 adapted to fit into an annular recess 19 formed between a pair of flanges 20 and 21 which are formed on a plunger 22 that extends downwardly through a sleeve or bushing 23 that is fastened as by welding to the base plate 6. The outer extremity of the plunger 22 is threaded at 24 to receive an adjusting nut 25 and a lock nut 26. Positioned between the extremity 21 of the bushing 23 and the nut 25, is a washer 28 on which rests the end of a compression spring 29, the upper end of which engages the plate 6. It will be seen from Figure 4, that by adjusting the nuts 25 and 26, the space between the washer 28 and the end 21 of the bushing 23 may be regulated and thereby govern the distance which the plunger 22 can be moved and, consequently, the amount of movement of Figure 5 is a side view of the cap-and-stop-plate between the lines 5—5 of Figure 2, wherein the plate is shown in dotted position.

25 30 35 In the various views, wherein like numbers refer to corresponding parts, 1 is the base of a topping apparatus having a vertically extending portion 2 having a stop 3 and carrying a topping lid 4 pivoted at 5 to the portion 2, all as disclosed in my patent and application previously referred to. My present improvements are directed to the parts carried on the base portion of the apparatus.

40 45 50 55 Mounted on the base 1, is a metal plate 6, preferably of steel treated to prevent rusting, which is held to the base 1 by screws 42. Fastened to the base plate 6, are four fixed standards or spreader members 7 symmetrically spaced on the plate 6, one for each side of a berry box or

the levers 11 is thereby regulated which, in turn, fixes the distance which the end 16 of the lever arm 12 is separated from the fixed spreader arm 7 at its end 9.

In practice, the apparatus is mounted on a table or bench 30 through which the plunger 22, sleeve or bushing 23 and spring 29 project. The threaded end 24 of the plunger 22 is adapted to be engaged by a lever 31 pivoted at 32 and operated by a foot treadle, not shown, thereby leaving both hands of the operator free to manipulate the box and the cover to be applied thereto.

Positioned within the confines of the fixed spreader arms 7, and above the flange 20 of the plunger 22, is a stop plate 33 having downwardly turned rim portions 34 which engage the base plate 6, the stop plate 33 being fastened to the plate 6 as by screws 35 shown in dotted position in Figure 2. The plate 33 has rim orifices 36 between the portions 34 for fitting over the lever arms 13 as shown in broken lines in Figures 2 and 4. The plate 33 thus acts to cover the arms 13 and the end of the plunger 22, and also acts as a stop and rest for the berry box.

As shown in Figure 1, the box is in position between the fixed spreader arms 7 and the plunger 22 has been moved upwardly to force the end portions 9 and 16 apart, leaving a space 37 to receive the flaps 38 of a cover 39 such as described in my application previously referred to. At this point, it may be mentioned that it is assumed that the box has been topped with berries by means of the topper lid 4 which is thrown back, as shown in Figure 3, all as explained in my Patent 2,318,483, and is now ready to receive the cover 39.

The cover 39 is applied as shown in Figure 3, by inserting the flaps 38 into the space 37 between the spreader arm ends 9 and 16. As soon as the cover 39 is in place, as shown in Figure 3, the force is released from the lever 31 and the spring 29 returns the plunger 22 to normal position, moving the arms 13 and 12 to cause the ends 9 and 16—for a considerable distance inwardly from their extremities—to engage the flaps 38 of the cover 39. The packaging is then completed and the box is lifted from the apparatus. While it is being lifted, it will be noted that there is a downward pull by the sprader fingers on the flaps 38, thereby holding the cover securely in position over the top of the box so that when the box is finally removed, the outer band 40, which has been spread away from the body portion 41 of the box, moves back substantially to normal position to grip the flaps 38.

It may be mentioned in passing that the band around the top of the berry boxes, as now constructed, is a one-piece affair, starting from the inside and going once around and then passing through to the outside at the junction of the two body strips, and making approximately $1\frac{1}{4}$ turns on the outside as indicated by reference to the left-hand side of Figure 1. However, by my construction as described, the box is very easily pushed into the position shown in Figure 1, whereby the cover flaps 38 are positioned between the body of the box and the adjacent outer portion of the band.

As heretofore explained, the adjustment of the lift plunger 22 determines the distance which the upper ends 9 and 16 of the spreader members are separated. Usually, this opening 37, which is somewhat exaggerated as shown in Figure 1, is preferably not over $1\frac{1}{8}$ ", which I have found to be sufficient to make an easy assembly of the cover

39 and which does not unduly stretch the box band between the band and box staples 43, so that when the box is removed from the apparatus, the band will come back and grip the cover tabs 38 so that the cover is held securely in position on the box. During the withdrawing of the box from the spreader pins, these pins apply a pull on the tabs so the cover is held snugly down on the box at the time when the ends of the spreader members pass out of contact with the band.

What I claim is:

1. Means for completing the packaging of berries or the like in a box having the usual type of rim, including the application to the box of a cover having ears or flaps adapted to be positioned between portions of the rim and the body of the box; said means including a base portion having upwardly extending, substantially rigid guide and support members spaced, one for each side of a box or container, a lever associated with each support member and pivotally mounted thereon, each lever having two stiff arms, one arm extending upwardly along the outside of its support member at least to a point near the end of the support member, the ends of both the support member and said arm being tapered toward each other and adapted to pass between portions of the rim and body of the box to spread them apart to receive cover ears, the other arm of the lever extending inwardly over the base, a hollow bushing extending downwardly from the base, a slideable plunger carried by the bushing and terminating above the base in an enlarged end having an annular recess to receive the ends of all of said inwardly projecting arms, means for adjusting the upward movement of the plunger when force is applied thereto, as well as the movement of said lever arms to determine the amount of separation between the levers and their cooperative support members, means for returning the plunger to normal position after force is removed therefrom and for closing the lever arms onto the cover ears which have been inserted between the lever and their cooperative support members whereby when the box is removed, the cover ears are left in what were said separations.

2. Means for completing the packaging of berries or the like as set forth in claim 1, further defined in that said means for returning the plunger to normal position is a spring which, after the plunger is returned to normal position, applies a force to said arms causing the upper arms to press the ears of the cover against said support members and thereby apply a pulling strain on the ears while the box is being pulled off the arms and cooperating supports.

3. Means for completing the packaging of berries or the like as set forth in claim 1, further defined in that a plate is provided for covering the upper end of the plunger and cooperating horizontally positioned lever arms and also serving as a rest for the box.

4. Means for completing the packaging of berries or the like as set forth in claim 1, further defined in that the plunger adjustment means comprises a threaded end on the plunger, a spring positioned around the hollow bushing, at least one nut on the threaded end of the plunger, and at least one washer between the nut and spring.

5. Means for completing the packaging of berries or the like as set forth in claim 1, further defined in that the guide and support members have considerable width to cover quite an area

of the box sides, the supports tapering in conformity to the box taper so the sides of the box slide down on the taper when putting the box into topping position.

6. Means for completing the packaging of berries or the like as set forth in claim 1, further defined in that the upper end of each guide and support member, and the vertically extending arm of its cooperating lever, normally come together so as to form, in effect, a single, relatively thin wedge for readily entering between the body of the box and the rim band.

7. Means for completing the packaging of berries or the like in a box having a body and band-type rim, said means including a topping apparatus and a cover having ears for engaging the box; the topping apparatus comprising a base having a plurality of fixed guide and support members arranged on the base to engage the sides of the box, and having their upper ends tapered away from the box, a bell-crank lever pivoted to each support member, one arm of the lever extending upwardly alongside of its support member and having its end tapered toward the taper on the support member, the other arm of the lever extending over the base toward the center thereof, a bushing fastened to the base and extending downwardly therefrom, a plunger extending through the base and bushing and having an enlarged head just above the base, said head having an annular recess therein to receive the ends of said inwardly projecting lever arms, a spring mounted on the sleeve and acting on the plunger to normally force it downwardly and thereby hold the upper ends of the lever arms in engagement with their respective support members, whereby the box may be readily inserted in position between the support members for topping, means for operating the plunger to cause the ends of the lever arms to move the rim portion away from the body of the box, whereby ears on a cover may, after the topping operation has been performed, be passed between the separated portion of the rim and body of the box, and between the lever end and the support end, the ears being slidably gripped between the lever and support ends when said plunger-operating means is released and the covered box is withdrawn from the structure.

8. Means for completing the packaging of berries or the like in a box having a body and band-type rim, as set forth in claim 7, further defined in that a plate for seating the box is provided to go over the inwardly projecting lever arms and plunger end, and further defined in that means are provided for limiting the upward movement of the plunger so the rim of the box may not be unduly spread away from the body thereof.

9. Means for completing the packaging of berries or the like in a box having the usual type of rim, including the application of a cover, having ears or flaps, to the rim; said means including a base portion having upwardly extending, substantially rigid guide and support members spaced, one for each side of a box, a lever having two stiff arms pivoted on each of said support members, one arm extending upwardly along the outside of its support member at least to a point near the end of the support member and said arm being tapered toward each other and adapted to pass between portions of the rim and body of the box to spread them apart, the other arm of the lever extending inwardly over the base, means for acting on the inwardly projecting lever arms to move the upwardly extending arms away from their fixed supports to provide spaces for the easy insertion of the flaps of a cover, and means for returning the levers to normal position whereby the cover flaps are engaged by the fixed supports and the upwardly extending lever arms as and for the purpose described.

10. An apparatus for finishing the packaging of berries including the application of a cover to the berry box having a band-type rim, the cover having tabs, one for each side of the box, said apparatus including a base having vertically extending spreader members supported thereon for movement toward and from each other, the spreader members being arranged in pairs spaced on the base so as to receive the box between the spaced pairs of members, each pair of spreader members having their upper extremities normally meeting to form in effect a single, relatively sharp wedge adapted to readily slip between the body of the box and the outer band of the rim when the box is placed in topping and covering position within the confines of the pairs of spreader members, means for moving the spreader members apart so the cover tabs may be inserted between the spreader members, means for closing the said members onto the tabs to securely pull the cover in place on the box while the box is being lifted from the members.

11. An apparatus for finishing the packaging of berries as set forth in claim 10, further characterized in that the spreader members are arranged on the base so their wedge-shaped ends will pass between the body of the box and the outer band of the rim between the location of the staples on their respective sides of the box, and further characterized in that the tabs on the box cover have a width closely approaching the distance between the band staples.

GALE HARRISON.

CERTIFICATE OF CORRECTION.

Patent No. 2,376,138.

May 15, 1945.

GALE HARRISON.

It is hereby certified that error appears in the printed specification of the above numbered patent requiring correction as follows: Page 1, second column, line 38, beginning with the words "Figure 5 is a" strike out all to and including "box or" in line 55, and insert the same before "container" in line 1, same page and column; and that the said Letters Patent should be read with this correction therein that the same may conform to the record of the case in the Patent Office.

Signed and sealed this 7th day of August, A. D. 1945.

Leslie Frazer
